ABSTRACT: The hammock frame is comprised of bent stock tubular members and angle iron members welded together to provide a base structure comprising end-to-end hinged base members to the outer ends of which are swingably journaled hammock support members. The hammock support members are foldable against their respective base members and the base members are foldable against themselves to provide a doubly folded compact unit. When erected, the central part of the base structure is somewhat elevated above the support floor to allow for flexing and resultant resilient inward yielding of the hammock support members.

COLLAPSIBLE SELF-SUPPORTING HAMMOCK

This invention relates to hammocks and is directed particularly to a novel and improved collapsible self-supporting hammock.

Various types of foldable stands or supporting structures for holding a hammock member in outstretched position for use have heretofore been devised. Such foldable or collapsible stands heretofore known, however, have been deficient in several respects, among which the following: their complexity, their lack of strength and resiliency, their lack of simple means for adjustment of the stretch of the hammock, their costly use of specially fabricated parts, and their bulkiness when in collapsed or folded condition.

It is, accordingly, the principal object of this invention to provide an improved collapsible, self-supporting hammock that obviates the above-described deficiencies.

A more particular object is to provide a collapsible, self-supporting hammock wherein the supporting framework is fabricated of stock metal tubular and angle iron parts and miscellaneous common hardware items for strength and economy of manufacture, the framework comprising a pair of base members centrally hinged and having, swingably mounted at their outer ends, upwardly extensible hammock support members, the hammock support members being foldable down against their respective base members, and the base members being foldable double against themselves to provide a compact unit for easy storage and portability.

Another object is to provide an improved collapsible hammock stand of the character above described wherein the framework base members, when extended for use, have their central portions elevated above the supporting surface to permit flexing in the downward direction and thereby to provide resiliency in the upwardly extending hammock support members for increased comfort of the hammock user without the provision of coil springs in the hammock member attachment chains.

Other objects, features and advantages of the invention will be apparent from the following description when read with reference to the accompanying drawings. In the drawings, wherein like reference numerals denote corresponding parts throughout the several views:

FIG. 1 illustrates, in perspective, a preferred form of collapsible self-supporting hammock embodying the invention;

FIG. 2 is a side elevational view of the hammock, on an enlarged scale;

FIG. 3 is a perspective view showing the hammock-supporting framework in fully collapsed or folded condition for transport or storage;

FIG. 4 is a perspective view showing the hammock-supporting framework in partially open or unfolded condition;

FIG. 5 is similar to FIG. 4 but shows the framework in fully unfolded or open condition ready for attachment of the hammock member; and

FIG. 6 is a fragmentary view, in side elevation and on an enlarged scale, of the central hinge mechanism comprising the supporting framework.

Referring now in detail to the drawings, S designates, generally, a collapsible supporting framework embodying the invention, and B the hammock member supported by the framework. The supporting framework S, which can readily be constructed, for the most part, of tubular and angle iron steel stock, (although it could also be made of extruded aluminum members), comprises opposed, relatively foldable base members 37 of heavy gage, tubular stock bent into elongated U-shape by semicircularly curved outer end portions 12 extending into spaced, parallel, side arm portions 11, 11 at each side. The inner ends of the side arm portions 11, 11 at each side of the framework are welded, along side portions thereof, against the horizontal inner face 13 of a length of angle iron 14, near the opposite ends thereof, the terminal edges of said side arm portions being welded against the vertical inner faces

15. A pair of spaced hinges 16 have their hinge leaves 17, 17 welded against the outsides of the horizontal inner faces 13 of the angle irons 14 (see FIG. 6) near the outer ends thereof (see FIG. 3) to permit folding together of said base members 5 as illustrated and as is hereinbelow more particularly described. As is best illustrated in FIG. 2, the side arm portion 11, 11 of each of the base members 37 is welded at a slight angle in the seats of their respective angle iron members 14 so that when unfolded, the hinges 16 are at their limit positions as determined by the abutment of the outer vertical faces of the angle iron members 14, 14.

Transverse tubular feet 18, 18 are welded against the underside of the base members 37 near the outer ends of the side arm portions 11, 11 thereof and just beyond the curved outer end portions 12. As is illustrated best in FIG. 3, one of the tubular feet 18 is arranged somewhat nearer the outer end of the supporting framework than the other, so that said feet will lie side by side when said framework is folded or collapsed. It will be noted that the feet 18 serve to further elevate the already slightly elevated central zone of the framework, as can best be seen in FIG. 2, to enhance the resiliency of the framework in use, as is hereinbelow more particularly described.

As is best illustrated in FIG. 5, strengthening tubular members 19, 19 are provided in each of the opposed, foldable base members 37 of the framework, being disposed in spaced, parallel relation between the side arm portions 11, 11 thereof. The inner ends of the strengthening members 19, 19 are flattened along upper portions thereof, whereat they are welded against the horizontal inner faces 13 of their respective angle iron members 14, so that the undersides of the inner ends of said strengthening members are displaced, for the most part, beneath said angle iron members, (see FIG. 6).

Upwardly extensible hammock support members 38 of tubing bent substantially into U-shape and defined by slightly divergent, opposed hammock arm members 20, 20 extending outwardly of an arcuate end portion 21, have the outer ends of said arm members journaled between the base member side arm portions 11, 11 near the outer ends thereof in the vicinity of the tubular feet 18, 18. The hammock support members 38 are each swingably journaled with respect to their associated base members 37 by means of journal rods 22 extending through transverse openings in the side arm portions 11, 11 and the hammock arm members 20, 20, said journal rods 45 preferably being welded to said side arm portions at their outer ends to retain them in place. As is best illustrated in FIGS. 4 and 5, the outer ends of the strengthening tubular members 19, 19 are secured, as by welding, against upper central portions of their associated feet 18, 18, and provide additional support for the journal rods 22 by the passage of said rods through transverse openings therein.

Means are provided for adjustably securing the hammock support member 38 in their substantially upright positions for supporting the hammock member B therebetween. To this end, lower and upper turnbuckle rods 25, 26, respectively, adjustably joined by a turnbuckle nut 27, are provided at each end of the supporting framework, the upper turnbuckle rod 26 being formed at its outer end with a collar 28 circumjacent the arcuate end portion 21 of it associated, upwardly extensible 60 hammock support member 38 at a central portion thereof and constrained therat against sideward movement as by welded-on abutment bosses 28, 29, at each side. The outer ends of the lower turnbuckle rod 25 are each formed with circular eyes 30 adapted to engage with a hook pin 31 welded to and extending angularly outwardly and sidewardly of the outer ends of the 65 respective curved outer end portions 12 of the foldable base members 37, said hook pins, as illustrated in FIG. 3, preferably being outwardly directed in opposite directions.

As illustrated in FIG. 4, when the hammock support members 38 are collapsed or folded inwardly to their fullest extend, their inner ends will abut the flattened inner end portions of the strengthening members 19, 19, and the lower turnbuckle rods 25 will be held in place against their strengthening members by means of resilient clips 23 fixed to and extending outwardly of each of said strengthening members.

It will be understood that the supporting framework, when in collapsed condition as is illustrated in FIG. 3, will be most compact for easy portability and storage. With the use of one inch tubular stock, total thickness will be only slightly greater than three inches. In setting the framework up for use, it will first be unfolded to the position illustrated in FIG. 4, as hereinabove described, after which the hammock support members 38 will be swung upwardly to their positions as illustrated in FIG. 5 and retained thereat by engaging the eyes 30 of their respective lower turnbuckle rods 25 on their associated hook pins 31.

The hammock member B, which is preferably of muslin, canvas or duck, is provided with the usual hemmed spreader rods 33 at each end, the ends of each of which rods are fitted with support chains 34, all of equal length and having hooks 35 at their outer ends adapted to engage in pairs of hook openings 36 in each of the hammock support members 38, said openings being provided in the arcuate end portions 21, thereof. In use, after the hammock member B is hooked in place on the framework as illustrated in FIG. 1 the turnbuckle nuts 27 at each end will be turned to shorten the turnbuckles, thereby correspondingly separating the hammock support members 38 at each end to stretch the hammock member B in place to the desired degree of comfort for the user.

It will be understood that as weight or change in weight is applied to the hammock structure by the user, forces tending to pull the outer ends of the hammock support members 38 together will be transmitted to the unfolded base members 37 which, because of their elevated inner limit positions as determined by their hinge connection, act in unison as a leaf spring, thereby affording a high degree of resiliency in a strong structure.

While I have illustrated and described herein only one form in which my invention can conveniently be embodied in practice, it is to be understood that this form is given by way of example only, and not in a limiting sense. The invention, in brief, comprises all the embodiments and modifications coming

within the scope and spirit of the following claims:

What I claim as new and desire to secure by Letters Patent is:

1. A collapsible self-supporting hammock comprising, in combination, a pair of elongated base members, hinge means swingably interconnecting inner end portions of said base members to permit relative movement between spread-apart and face-to-face limit positions, a pair of elongated hammock support members, means swingably interconnecting the inner end each of said hammock support members to outer end portions of said base members for movement between outstretched and relatively inwardly folded positions, turnbuckle rod mechanisms interconnecting the outer ends of said hammock support members with the outer ends of their respective base members for adjustably securing said hammock support members in their outstretched positions, said hammock support members, when in their inwardly folded positions, lying against one side of their respective base members, said base members, when in their face-to-face limit positions, being face to face with respect to their other sides, said base members comprising tubular metal members bent into U-shape to define closed, arcuate outer end portions and open, spaced-apart inner free end portions, and said hammock support members comprising tubular metal members bent substantially into U-shape, the free ends of said hammock support tubular members being swingably journaled to end portions of their respective base members just beyond their arcuate portions by means of a transverse journal rod, said other sides of said base members, when said base members are in their spread-apart limit positions, meeting at an angle slightly less than 180 degrees, said base members swingably interconnecting means comprising a pair of angle iron members one for each of said base members, the inner free ends of said base tubular members being welded into the channel recesses of their respective angle iron members, and hinge means welded between outer faces of said angle iron members.
